(57) **CLAIM**

The ornamental design for a container for pouches of smokeless tobacco, as shown and described.

DESCRIPTION

FIG. 1 is an exploded perspective view of a first embodiment of a container for pouches of smokeless tobacco showing our new design;

FIG. 2 is a top plan view thereof without the lid;

FIG. 3 is a side view thereof without the lid;

FIG. 4 is a side view thereof with the lid;

FIG. 5 is a top plan view of the container, shown without the lid and illustrating the pouches of tobacco ready for use;

FIG. 6 is an exploded perspective view of a second embodiment of a container for pouches of smokeless tobacco showing our new design;

FIG. 7 is a top plan view thereof without the lid;

FIG. 8 is a side view thereof without the lid;

FIG. 9 is a side view thereof with the lid;

FIG. 10 is a top plan view of the container, shown without the lid and illustrating the pouches of tobacco ready for use;

FIG. 11 is an exploded perspective view of a third embodiment of a container for pouches of smokeless tobacco showing our new design;

FIG. 12 is a top plan view thereof without the lid;

FIG. 13 is a side view thereof without the lid;

FIG. 14 is a side view thereof with the lid; and,

FIG. 15 is a top plan view of the container, shown without the lid and illustrating the pouches of tobacco ready for use.

The broken lines in the drawings represent unclaimed environmental subject matter.
